INVENTOR.

Charles Rodenbaugh
By May H. St. John
his ATTORNEY.

UNITED STATES PATENT OFFICE.

CHARLES RODENBAUGH, OF PITTSBURGH, PENNSYLVANIA.

TRUSS.

1,225,177.

Specification of Letters Patent.

Patented May 8, 1917.

Application filed September 20, 1916. Serial No. 121,102.

To all whom it may concern:

Be it known that I, CHARLES RODENBAUGH, a citizen of the United States of America, residing at Pittsburgh, county of Allegheny, and State of Pennsylvania, have invented 5 certain new and useful Improvements in Trusses, of which the following is a specification.

This invention relates to trusses and has 10 for its object to provide a device of such class, with means in a manner as hereinafter set forth to overcome inconvenience and annoyance when wearing the truss.

A further object of the invention is to provide 15 a truss having means in a manner as hereinafter set forth, capable of shifting with the movements of the body so that the truss can be worn with ease and comfort.

Further objects of the invention are to 20 provide a truss which is comparatively simple in its construction, strong, durable, light, adjustable, efficient and convenient in its use, readily positioned, and comparatively inexpensive to manufacture.

25 With the foregoing and other objects in view the invention consists of the novel construction, combination and arrangement of parts, as hereinafter more specifically described and illustrated in the accompanying drawings, wherein is shown an embodiment 30 of the invention, but it is to be understood that changes, variations and modifications can be resorted to which come within the scope of the claims hereunto appended.

35 In the drawings wherein like reference characters denote corresponding parts throughout the several views:

Figure 1 is a side elevation of a truss in accordance with this invention.

40 Fig. 2 is a top plan.

Fig. 3 is a like view with the cover plate removed.

Fig. 4 is a similar view with the cover plate and inclosing plate removed.

45 Fig. 5 is a like view of the body portion of the truss.

Fig. 6 is a longitudinal sectional view through the center of the truss.

Referring to the drawing in detail 1 50 notes the truss body and 2 the rocker element or section of the truss.

The truss body is formed of an outer hol-

low section 3 and an inner shiftable section 4. The hollow section 3 is substantially oval-shape in cross-section and provides a 55 cavity 5 for the section 4 and the connection thereof with the section 3.

The section 3 at its top is formed with a pair of laterally apertured extensions 6, 7, and the openings in each of said sections are 60 indicated at 8 and are adapted to receive supporting straps for the truss body 1. The extension 7 is formed with a vertically disposed lip 9 for a purpose to be presently referred to.

65

The section 3 is constructed of light metallic material and is somewhat frusto conical in contour and has its outer face, as well as its bottom and its inner face inclosed by a strip of soft material, as at 10. The material 10 is preferably chamois skin and provides a cushion. If desired however, an additional packing can be interposed between the strip 10 and the metallic part of the section 3. The strip 10 upon the outer face of 75 the section 3 extends to the projections 6, 7, and is maintained in position upon the outer face of the section 3 by binding wire 11, which is inclosed by a leather band 12.

70 The strip 10 is maintained against the bottom of the section 3, as well as against the inner face thereof, by a retaining plate 13 which is arranged against the top wall of a cavity 5 and secured in position by screws or rivets 14. The plate 13, in connection with 80 the wire 11, tightly maintains the strip 10 in position against the metallic part of the section 3.

85 As the top of the section 3 and plate 15 is rounded, it is maintained in position by 90 the screws 14 and also screws 16. The plate 15, centrally thereof, is provided with an opening 17 which registers with an opening 18 in the top of the cavity 5. The opening 18 registers with an opening 19 formed in 95 the strip 10 and said opening 19 registers with an opening 20 provided in the plate 13.

The plate 15 is cut-away at each end, as at 21, so as not to overlap the opening 8 in the projections 6, 7, and be free of the lip 9.

100

Fixedly secured to the upper face of the plate 15 over the opening 17, is a disk 22 having a centrally disposed opening 23, with the wall thereof threaded. Formed integral

with the plate 15 and arranged parallel with the disk 22 is a pair of vertically disposed lugs 23', each provided with an aperture 24 for a purpose to be presently referred to.

5 The section 4 is formed with light metallic material and is inclosed by a flexible strip 25, preferably of chamois, although any other suitable material can be employed. It will also be stated that, if desired, a soft 10 packing can be interposed between the strip 25 and the metallic portion of the section 4. The strip 25 completely incloses the metallic portion of the section 4 and is maintained in position by a retaining plate 26 arranged 15 at the top of the section 4 and secured in position by screws 27. The plate 26 has a pocket 28 which communicates with an opening 29 arranged centrally of the plate 26.

The section 4 is of a size to be clear of the 20 wall of the cavity 5 so that the said section 4 can shift therein when desired, as well as being vertically adjustable within said cavity 5. The section 4 includes means for vertically adjusting it, as well as suspending it, 25 within the cavity 5. Said means consists of a vertically disposed screw 30, having its head 31 arranged within the pocket 28. The head 31 being materially less in size than the pocket 28 so that the section 4 can shift 30 upon said head when desired. The opening 29 in the plate 26 is of slightly greater diameter than the diameter of the screw 30.

Mounted upon the screw 30, as well as engaging therewith, is an adjusting member 32, which has a reduced peripherally threaded extension 33, having threaded engagement with the threads of the wall of the opening 23. The adjusting member 32 extends up through the openings 17, 18, 19 40 and 20.

The rocker section 2 comprises a base plate 34 which has its lower face inclining downwardly from each end toward the center and said base plate 34, centrally thereof, is 45 formed with an opening 35 to provide a clearance for the disk 22, screw 30 and reduced threaded extension of the adjusting member 32. The sides of the base plate 34 are cut-away, as at 36 and into said cut-away portions extend the lugs 23'. The base plate 34 is pivotally connected with the lugs 23' by the pivots 37.

Connected to the upper face of the base plate 34, by securing devices 38, are retaining springs 39. Mounted over the straps or springs 39 for concealing those ends which are connected to the base plate 34 is a plate 40, having an opening 41. The plate 40 is inclosed by a cover plate 42.

60 The lip 9 is employed to prevent pinching of the flesh when the body 1 moves relatively to the body 2 or vice versa.

The manner of connecting the body 1 to the section 2 permits of the shifting thereof 65 so as not to cause any annoyance to the

wearer when using the truss, or in other words so that the truss can be worn with ease and comfort.

What I claim is:—

1. A truss comprising a body portion consisting of a pivoted outer section having a cavity and a loosely mounted and vertically adjustable inner section arranged in said cavity, and a rocker element having the outer section of said body pivotally connected therewith and provided with means for connecting the truss in position upon the body of the wearer, said pivoted outer section of said truss body having a pair of oppositely disposed apertured extensions for the reception of supporting straps, one of said sections provided with a lip overlapping one end of said element. 70

2. A truss comprising a body portion consisting of an inner and outer section, said outer section having a cavity in which is arranged said inner section, means connected with said outer section and with said inner section to vertically adjust the latter relatively to the former, said inner section 85 loosely mounted upon said means, and a rocker element pivotally connected with said outer section and provided with straps, the top of said outer section being flat and the lower face of said rocker element inclining downwardly from each end toward the center and said rocker element having means to constitute a clearance for the means for vertically adjusting said inner section. 95

3. A truss comprising a body portion consisting of an inner and outer section, said outer section having a cavity in which is arranged said inner section, means connected with said outer section and with said inner section to vertically adjust the latter relatively to the former, said inner section 100 loosely mounted upon said means, and a rocker element pivotally connected with said outer section and provided with straps, said outer section provided with a pair of oppositely disposed apertured projections for the reception of supporting straps. 105

4. A truss comprising a body portion consisting of an outer section provided with a cavity and an inner section arranged within said cavity, means carried by the outer section and connected with the inner section for vertically adjusting the latter, said inner section loosely mounted upon the means to permit of the shifting of the inner 110 section within the cavity, and a rocking element pivotally connected with the top of said outer section, the top of said outer section being flat and the lower face of said rocking element inclining downwardly 115 from each end toward the center. 120

5. A truss comprising a body portion consisting of an outer section provided with a cavity and an inner section arranged within said cavity, means carried by the outer 125

section and connected with the inner section for vertically adjusting the latter, said inner section loosely mounted upon the means to permit of the shifting of the inner section 5 within the cavity, and a rocking element pivotally connected with the top of said outer section, the top of said outer section being flat and the lower face of said rocking element inclining downwardly from 10 each end toward the center, said rocking

element provided with means to provide a clearance for the means for vertically adjusting said inner section.

In testimony whereof I affix my signature in the presence of two witnesses.

CHARLES RODENBAUGH.
